INSOLE AND METHOD OF MAKING SAME

Isaac F. Damon, Belmont, Mass., assignor to
Compo Shoe Machinery Corporation, New York,
N. Y., a corporation of Delaware

Application March 18, 1936, Serial No. 69,491

5 Claims. (Cl. 12—146)

This invention relates to the manufacture of foot wear, and more particularly to the making of shoes having an improved insole construction.

General objects of the invention are to provide 5 a novel and improved form of insole, having relatively thick and thin portions, which is better adapted to fit in a completely assembled shoe.

Another object of the invention is to provide an improved insole having a central forepart 10 portion which is thicker than the remainder thereof, so as to provide integral filler material adapted to occupy space which would otherwise have to be compensated for in shoes of the various types to which such insole is applicable.

15 Other objects of the invention are to provide a method of making an insole having improved characteristics such as those indicated above, and to provide methods of making shoes involving utilization of such an insole.

20 Other objects of the invention will in part be obvious and will in part appear hereinafter.

The invention accordingly comprises the several steps and the relation of one or more of such steps with respect to each of the others, and the article possessing the features, properties, 25 and the relation of elements, which are exemplified in the following detailed disclosure, and the scope of the invention will be indicated in the claims.

30 For a fuller understanding of the nature and objects of the invention reference should be had to the following detailed description taken in connection with the accompanying drawing, in which:

35 Fig. 1 is a perspective view of a rounded insole blank used in the construction of an insole embodying the principles of this invention;

Fig. 2 is a perspective view of an insole made from the blank of Fig. 1;

40 Fig. 3 is a fragmentary illustration of one form of apparatus provided to make the insole of Fig. 2;

Fig. 4 is a transverse vertical sectional view 45 across the forepart of one form of shoe embodying the insole of the present invention; and

Fig. 5 is a transverse vertical sectional view taken across the forepart of another form of shoe utilizing such insole.

Referring more particularly to the drawing, 50 there is shown a rounded insole blank 10 formed of compressible material such as a manufactured composition of plant fibers or the like. Such insole materials are well known to the trade, one such, for example, being commercially available 55 under the trade name Onco. Any such material is suitable for the purposes of this invention, provided it is capable of being compressed or moulded under pressure and is able to retain the form which it is thus compelled to assume.

60 The blank 10, formed of such a material, is

initially somewhat thicker than the required thickness of the finished insole. An insole having a raised landed portion 11 at its central forepart is formed from such blank by compressing the heel portion 12 and shank portion 13 thereof up to the ball line and by further compressing the marginal forepart portion 14 while leaving the central forepart portion 11 uncompressed. This compressing operation decreases the thickness of the pressed parts and also may slightly laterally expand them, so that the blank 10 may initially be somewhat smaller in dimension than the required insole, or the latter may after compression be trimmed to the required size by any known or suitable trimming equipment. Compression of the heel, shank and marginal forepart portions causes these parts to become denser than the initial stock, and makes them thinner while retaining and even enhancing their initial strength, which is desirable. The non-compacted central forepart portion, while preserving the added relative thickness to act as a filler to compensate for the upper lasting allowance, also retains its initial relatively low density and high flexibility.

25 This compression of the insole blank may be effected in various ways, one suitable apparatus therefor comprising a pair of pressure rolls 15 and 15' (Fig. 3), one of which has a depression or matrix 16 corresponding in outline with the land 11 which is to be formed on the insole. A blank 10 is suitably registered with respect to the matrix 16 and is run between the rolls, which are spaced so as to compress the required portions of the insole while leaving the land 11 at substantially its initial thickness. Other forms 30 of pressing equipment may be used, however; for example, if desired the heel and shank portions may be squeezed between rollers up to the ball line, and the marginal forepart portion 14 may thereafter be compressed between other pressure rollers which are mounted so as to enable the stock to be inserted edgewise between. Pressing die equipment of suitable configuration 35 may also be used if desired.

40 Such an insole, having an integral landed portion at its central forepart, may be used to advantage in various shoe assemblies, two illustrative assemblies being shown in Figs. 4 and 5.

45 In Fig. 4 there is shown a shoe which is adapted to be lasted substantially along the lines of the McKay process, as is commonly done, for example, with many cemented shoe constructions. Here, the insole is located along the bottom of a last 17 with its landed portion 11 facing outwardly. An upper 18 is then pulled over and lasted to the heel and shank portions of the insole and to the relatively thin marginal portion 14 thereof. The lasting allowance 18' of such upper is trimmed so as to approach but not over-

lap the shoulder dividing the edge of the landed portion, and the latter is of such thickness that it substantially occupies the space between the inturned edges of the lasting allowance. Heretofore it has been customary to fill this space with a loose cork filler, or some other form of separate filler material. The present arrangement, wherein the lasting allowance 18' and the thicker insole portion 11 provide a substantially flat even surface at the bottom of the forepart of the upper, successfully eliminates such loose filler materials, which are liable to become dislodged and to gather into undesirable lumps or masses during the wear of the shoe, and also provides a comparatively flexible construction.

An outsole 19, the flesh surface of which may be flat, is placed against the bottom of the lasted upper and attached thereto in any suitable manner, the flat surface of the forepart of the upper being adapted snugly to fit thereagainst.

Any suitable form of lasting and sole-affixing operations may be employed, but preferably these are carried out through the use of pyroxylin cement, which may be applied between the upper 25 and the insole and between the outsole and the lasting allowance of the upper.

In Fig. 5 another form of shoe utilizing the insole of Fig. 2 is shown. The general construction of such shoe is somewhat similar to that shown in Fig. 12 in the copending application of Frank Maiellano, Serial No. 36,057, filed August 14, 1935. As is described in greater detail in that application, an outsole 20 is provided with a slightly raised land 21 at its central forepart portion by splitting a thin ply from the heel, shank and marginal forepart portions of the flesh side thereof, while leaving such land at the central forepart area and forming a corresponding aperture in the central forepart area of the split-off 40 ply. This ply, designated 22, is then assembled with an insole such as that shown in Fig. 2, being cemented to the flat face thereof on the reverse side from the insole land 11. The ply 22 and the insole may be trimmed so as to be marginally coextensive either before or after such cementing operation.

The composite insole thus formed is located on a flat bottom last 17 with the ply 22 facing thereagainst. An upper 23 is then pulled over and its lasting allowance 23' is attached to the insole, preferably by means of cement. The lasting allowance of the forepart is trimmed so as to approach but not overlap the land 11 on the insole, and the latter, in turn, is constructed so as to be substantially coextensive with the aperture formed in the insole ply 22. The outsole 20 is then located against the bottom of the lasted upper with its land 21 facing and supported by the thicker landed portion of the insole, cement 55 having been applied or activated between the marginal portions of the outsole and lasted upper. The outsole is then pressed to the upper in any suitable or known type of sole-affixing press having a pressure-applying pad or diaphragm.

65 A shoe constructed in this manner will at its interior forepart portion resemble in appearance the now popular shoe construction, wherein a landed outsole is mated with an apertured insole, since it will present to view the looped or 70 apertured insole ply 22, which is flush with and exposes the interior surface of the insole stock 10. Because of the presence of the thickened insole portion 11, a shoe of this general construction can be assembled on a flat bottom last without 75 danger of depressing the central area of the out-

sole forepart during the affixing operation, as will be more clearly understood from the description in the above mentioned application, Serial No. 36,057, as well as in another copending application of Frank Maiellano, Serial No. 36,056, filed August 14, 1935, wherein this problem of lasting shoes having landed outsoles and complementary insoles on flat bottom lasts is fully discussed. While two illustrative shoe constructions have been shown, it will be understood that the insole 10 of the present invention is usable in various types of shoes wherein a thickened filler piece is required at some portion of the shoe.

It will be seen that there have been provided a method and a construction which are well suited to fulfill their intended functions.

Since certain changes in carrying out the above process, and certain modifications in the article which embody the invention may be made without departing from its scope, it is intended that 20 all matter contained in the above description or shown in the accompanying drawing shall be interpreted as illustrative and not in a limiting sense.

It is also to be understood that the following 25 claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. An insole formed of relatively easily compressible material having permanently uniformly compressed relatively thin heel, shank, and marginal forepart portions and a thicker relatively uncompressed central forepart portion of lesser density and greater flexibility than said shank and heel portion.

2. A method of forming an insole which comprises providing an insole blank of relatively easily compressible and substantially inelastic material, and compacting the heel, shank, and marginal forepart portions thereof until they are thinner than the remaining central forepart portion, said latter portion being of lesser density and greater flexibility than said heel and shank portions.

3. A method of forming an insole which comprises providing an insole blank of compressible material having greater thickness and less area than the required insole, and compacting the heel, shank and marginal forepart portions of said blank until they have the required insole thickness and area, while leaving the central 55 forepart portion relatively thicker, less dense and more flexible than said compacted portions.

4. An insole formed of compressible material having permanently compressed relatively thin heel, shank, and marginal forepart portions and a thicker relatively uncompressed central forepart portion, said thin portions having all of the initial strength and said thicker portion having all of the initial flexibility of said material.

5. A method of forming an insole which comprises providing a compressible insole blank of initially substantially uniform thickness, and permanently compacting the heel, shank, and marginal forepart portions thereof until they are thinner than the remaining central forepart portion whereby the latter portion retains the initial flexibility of said blank and said compacted thinner portions retain at least the initial strength for lasting purposes of said blank.

ISAAC F. DAMON. 75
